UNITED STATES PATENT OFFICE.

GEORGE BALL, OF PHILADELPHIA, PENNSYLVANIA, ASSIGNOR TO WHITING-PATTERSON COMPANY, INCORPORATED, A CORPORATION OF PENNSYLVANIA.

TRANSFERRING MECHANISM.

Original application filed October 24, 1917, Serial No. 198,224. Now Patent No. 1,313,248. Divided and this application filed August 1, 1919. Serial No. 314,780.

To all whom it may concern:

Be it known that I, GEORGE BALL, a citizen of the United States, and a resident of the city of Philadelphia, county of Philadelphia, and State of Pennsylvania, have invented certain new and useful Improvements in Transferring Mechanisms, of which the following is a specification, reference being had to the accompanying drawings.

10 My invention relates to mechanism for conveying or transferring blanks or sheets as may be desired in various types of machines, being adapted for use with, although not limited to, machines for the production 15 of what are commercially known as window envelops, that is, envelops having an opening in the face covered by a piece of transparent or translucent paper through which the address on the contents of the envelop 20 may be read; a principal object of my invention being to combine various means and instrumentalities to form an efficient mechanism for transferring or conveying blanks from one part of a machine to another as 25 may be desired in the cycle of operations of any machine utilizing blanks of this character in the manufacture of its product.

My invention further includes all of the various other objects and novel features of 30 construction and arrangement hereinafter more definitely specified and described, this application being a division of my prior application for envelop machines, Serial No. 198,224, filed October 24, 1917.

35 To accomplish these and other functions hereinafter more specifically set forth, I may employ any means and instrumentalities suitable for effecting the results desired, and I do not, therefore, limit myself specifically 40 to those means and instrumentalities which I have herein illustrated and described for the purpose of enabling persons skilled in the art to make, construct and use my invention.

45 For the purposes of illustration merely, I have shown my invention as applied to a well-known form of reciprocating envelop machine primarily comprising means for supporting the envelop blank, means for gumming the blank on the back and seal flaps; means for feeding the gummed blanks to a creasing plate, a vertically reciprocating creasing plunger, and means for folding the gummed blanks into completed envelops,

all of these operations and the means generally employed to effect them being familiar to those skilled in the art, and I have, therefore, illustrated somewhat diagrammatically only those portions of the envelop machine necessary to a clear understanding of my invention.

In the drawings accompanying and forming a part of this specification, Fig. 1 is a side elevation of my invention, certain parts being broken away and other parts being shown in vertical section for the sake of clearness. Fig. 2 is a view in elevation, and also partially in vertical section, of my invention, portions of an envelop machine proper being also shown, Fig. 3 is a similar view, partially in section, of details thereof, and Fig. 4 is a fragmentary view, partially in vertical section and partially in elevation, of other details thereof.

My invention is shown herein for transferring a patch of a window envelop, after it has been severed from a continuous web by the operation of a knife, to a gummed envelop blank positioned beneath a creasing plunger 10' and includes broadly a suitable patch conveyor, means for moving the conveyor from adjacent a table to a position beneath the creasing plunger, and means for causing the patch to adhere to the conveyor during this movement. More specifically 75 said means may comprise a yoke-shaped conveyor 10, best shown in Fig. 2, the distance 80 between the arms of the yoke being preferably 85

somewhat less than the length of a patch A, which, of course, is equal to the 90 width of the web W, the arms of the yoke being preferably rectangular or substantially rectangular in cross section. The conveyor is provided with an upwardly projecting stem 11 rigidly connected with a 95 flanged block 12 arranged for longitudinal reciprocation in a swinging housing 15 provided with a slot 16 in which the block is arranged to engage and which forms a 100 guide therefor, a keeper plate 17 secured to the block and projecting over the edges of the slot on one side of the housing and the flange on the block projecting over the edges of the slot on the other side of the housing 105 serving to prevent the lateral displacement of the block, while a rod 19 extending above and below the block and slidably in suitable longitudinally extending apertures in the

housing serves as an additional guiding means to preserve the proper alignment of the block and the housing. The housing adjacent its upper extremity is rigidly secured to, and therefore rotatable with, a transversely extending shaft 22 journaled in a suitable bracket 23 secured to the frame of the machine and carrying, adjacent its outer extremity, a crank 24 connected by a link 25 with one end of a bell crank lever 26 pivoted on a shaft 28 journaled in brackets 30, and having at its opposite end a cam roll 30 arranged for engagement with the face of a cam 31 on cam shaft 39, a spring 32 attached to the bell crank lever and to some suitable portion of the frame of the machine serving to constantly maintain the cam roll and cam in contact. It will thus be evident that any movement of the bell crank lever due to the rotation of cam 31 will result in a movement of crank 24 and partial rotation of shaft 22, thereby imparting to housing 15, and in turn to conveyor 10, a swinging movement about the axis of shaft 22 as a center, the extent of which is primarily determined by the configuration of the face of cam 31 and relative proportions of the arms of bell crank lever 26.

For the purpose of causing the conveyor to assume the proper positions—in this case for removing the patch from a table 44 and delivering it beneath the creasing plunger—means are provided for effecting a relative movement between the conveyor and the housing, comprising, in the form of the invention shown, a member 40' having a curved slot 41 adapted to receive a roller 42 carried by block 12, as best shown in Fig. 2, the member being pivoted to the frame 30 of the machine upon a stud 43 and connected through a suitable link 45 with one arm of the bell crank lever 46, in turn pivoted on shaft 28 and having adjacent the outer end of its opposite arm a cam roller 49 engaging a suitable cam 48 on main cam shaft 39, a spring 51 connected to the bell crank lever and to some suitable part of the frame of the machine serving to maintain the cam roller and cam in constant contact, so that the rotation of the cam will effect a movement of member 40' about stud 43 in turn effecting a movement of block 12 in housing 15 and a resulting movement of conveyor 10 for a purpose to be hereinafter described.

Means are also provided to cause the patch to adhere to the conveyor during the movement of the latter from a position adjacent table 44 to a position adjacent the envelop 60 blank to which the patch is to be applied, and for this purpose the conveyor is provided with one or more internal apertures or passages 60 terminating at the extremities of the conveyor and communicating through 65 flexible piping 62 with a vacuum pump

which may comprise a cylinder 65 open at one end and having a piston 66 actuated through a bell crank lever 67 pivoted to the frame of the machine and operated through a link 68 from a suitable cam (not shown) 70, although, if desired, the pump may be of any other preferred construction. Means are also provided, as best shown in Fig. 4, for releasing the vacuum in the pump, and in turn in the conveyor, at the proper point 75 in the cycle of operations of the machine; for example, a valve 70 operative to close a port 71 in the cylinder 65 and actuated through a suitable link 72 by means of a bell crank lever 73 pivoted to one of the 80 brackets 40 and carrying a cam roll 74 maintained in contact with a suitable cam 75 on main cam shaft 39 by a suitably positioned spring 78, the cam being adapted to raise valve 70 against the tension of 85 spring 78 to open port 71 and release the vacuum in the cylinder at the proper point in the cycle of operations as hereinafter described.

In order to permit the conveyor to bring the patch into proper registration with any other part of a machine, such as adjacent the creasing plunger 10 in this case, the plunger 10 is provided with a pair of suitably disposed slots 80 of sufficient size to receive 90 the arms of the conveyor so that it can assume a position substantially parallel to the plunger shaft, and, similarly, to enable the conveyor to engage the paper beneath a retaining element on table 44, the former, as 100 well as any other portions are also provided with similar slots 82, as best shown in Fig. 1.

The parts having been constructed and assembled in connection with a suitable envelop machine preferably substantially as 105 described, the operation may be briefly indicated as follows: Presuming the parts to be in substantially the position shown in Fig. 1, a continued rotation of shaft 39 first causes cam 31 to actuate bell crank lever 26 110 to swing housing 15, and in turn conveyor 10, rearwardly toward table 44, member 40' remaining substantially stationary until the housing has completed about two-thirds of its rearward swing, when, through the actuation of bell crank lever 46 under the influence of cam 48 the extremity of curved member 40' is depressed, thus forcing the conveyor radially outwardly with respect to the housing to cause it to register with that 115 portion of web W which has been fed onto table 44, the portion having been severed to form a patch. Substantially simultaneously with this operation, a vacuum is formed within cylinder 65 and in turn within the 120 conveyor, thus causing the severed patch to adhere to the latter. The continued rotation of shaft 39 now brings the cam 48 into position to swing the outer extremity of member 40' upwardly to raise the con- 125 130

veyor with its adhering patch away from table 44 sufficiently to permit the patch to clear the table during the forward swing of the conveyor which now commences and which is effected by the action of cam 31 whose continued rotation lifts the outer end of bell crank lever 26 to swing the housing forwardly to assume a position parallel with the creasing plunger shaft, thus bringing the patch into suitable position over the blank. Simultaneously with the termination of the forward swing of the conveyor, member 40' is caused to swing slightly downwardly thereby lowering the conveyor vertically towards the blank, the vacuum in the conveyor being simultaneously released under action of cam 75 to free the latch from the conveyor. After this has been done the cam 48 operates to raise the lower end of the conveyor or member 40' upwardly a sufficient distance at which the lower end of the conveyor will assume its normal initial position described above at the beginning of the cycle of operations.

While I have herein illustrated and described with considerable particularity a preferred embodiment of my invention and have shown the same in connection with an envelop machine, I do not thereby desire or intend to limit myself specifically to such embodiment of my invention, or to its use in connection with an envelop machine identical with that to which I have referred, or to envelop machines generally, as suitable changes and modifications may be made in the details and arrangement of the various means and instrumentalities employed, and the invention may be adapted for use in connection with other forms of machines, without departing from the spirit and scope of the invention as defined in the appended claims.

Having thus described my invention, I claim and desire to protect by Letters Patent of the United States:

1. In a transferring mechanism, a housing movable about a fixed axis, a patch conveyor carried by said housing and movable relatively thereto, means operative to move

said housing, a movable slotted member operative to position said conveyor with respect to said housing, and means operative to cause the movement of said member.

2. In a transferring mechanism, a swinging housing, means operative to swing said housing, a patch conveyor movable with said housing and relatively movable with respect thereto and means comprising a vertically movable pivoted slotted member operative to effect the movement of said conveyor with respect to said housing at predetermined periods with relation to the movement of said housing.

3. A transferring mechanism including a housing adapted to be oscillated about a fixed axis, a conveyor carried by said housing, slotted means operative to positively reciprocate said conveyor in the housing radially with respect to said axis, means operative to retain a sheet on said conveyor and means to render said last-mentioned means operative and inoperative at predetermined periods.

4. In a transferring mechanism, the combination of a swinging housing, a conveyor, slotted means effective to cause positive reciprocation of the conveyor therein, means associated with the conveyor adapted to retain a sheet thereon and means automatically operating to render said last-mentioned means operative and inoperative at certain predetermined periods of operation of said transferring mechanism.

5. A transferring mechanism including a housing adapted to swing about a fixed axis, a member carried by said housing adapted to be reciprocated radially with respect to said axis, slotted means operative to positively reciprocate said member, conveying means carried by said member and means associated with said conveyor for retaining a sheet thereon, including a vacuum creating means and cam operated means for automatically controlling the operation of said sheet retaining means through said vacuum.

In witness whereof, I have hereunto set my hand this 30th day of July, 1919.

GEORGE BALL.
